UNITED STATES PATENT OFFICE

LEO RANNEY, OF NEW YORK, N. Y., ASSIGNOR TO STANDARD OIL DEVELOPMENT COMPANY, A CORPORATION OF DELAWARE

METHOD AND MEANS FOR WORKING OIL SANDS

Application filed January 13, 1927. Serial No. 180,793.

This invention relates to improvements in the recovery of oil from the earth by mining methods of the general type described and claimed in my U. S. Patents Nos. 1,634,235 and 1,634,236 granted June 28, 1927.

In accordance with the present invention, a gas adapted to facilitate flow of oil is forced into the oil sand in a manner to be described, and means are provided for the effective use 10 of such gas and the collection of oil.

As described in the patents above mentioned, the mining method involves the sinking of a shaft to a point adjacent an oil sand; the driving of galleries from the shaft above 15 or below the sand and adjacent to it, but spaced therefrom; the drilling of mine wells into the sand, and the collection of oil flowing from the mine wells.

The present invention will be fully understood from the following description read in connection with the accompanying drawings, in which

Fig. 1 is a vertical section through a mine gallery for the collection of oil;

25 Fig. 2 is a transverse section on the line II-II of Fig. 1;

Fig. 3 is a diagrammatic vertical section showing the lines of flow of gas and oil;

Fig. 4 is a diagrammatic plan view showing one method of operating an oil field;

30 Fig. 5 is a view similar to Fig. 3, but showing a modified method of introducing a gas into the sand.

Referring to the drawings, reference numeral 1 denotes a mine gallery driven in a lower cap rock 2 underlying an oil sand 3. An upper cap rock 4 covers the oil sand. Nipples or conduits 5 are set in holes 6 drilled upwardly into the lower cap rock, but not 40 through into the oil sand. The holes may be drilled vertically, or at an angle as shown in Fig. 2. The lower part of each hole 6 is enlarged to receive a sealing material 7 (cement, lead wool, or the like), which makes a 45 fluid-tight seal between the cap rock 2 and the nipples 5. The drilled openings 8, forming extensions of holes 6, tap the oil sand and form what I term "mine wells". Openings 8 are preferably enlarged at their ends 50 by reaming or blasting to form fluid-collect-

ing or distributory areas 9, as subsequently described.

Referring to the mine well installation shown at the left of Fig. 1, a gate valve 10 is fitted at the end of a nipple 5 and is connected with a cross-fitting 11. The lower arm of the cross is closed by a removable cap 11'. The horizontal arms of the cross are connected to elbows 12 and 13, and these in turn lead into pipes 14 and 15 extending downwardly into a trough 16 cut into the floor of the gallery. The pipe 15 is connected to an oil-collecting conduit 17 resting on the bottom of the trough. This conduit leads to a separator (not shown) in which oil may be separated from gas and water, if necessary, before the oil is pumped to the earth's surface. The pipe 14 is connected with a gas-conveying pipe 18. Pipes 14 and 15 have valves 19 and 20, respectively, so that either or both of these pipes may be shut off.

Referring to the construction shown at the right hand side of Fig. 1, the sealed nipple 5 and gate valve 10 are as above described, but a T-fitting 21 is used instead of the cross-fitting 11. The lower arm of the T-fitting has a removable cap 21'. An elbow 22 leads from the T-fitting and is connected with a pipe 23 which discharges into the oil collecting conduit 17. This type of equipment 55 may be used exclusively for the withdrawal of oil, a separate fitting 5' being connected to the gas line 18 only (Fig. 3).

It is generally desirable to form a mine gallery entirely around the area to be worked, for example a 40 acre tract, diagrammatically shown in Fig. 4. In this figure, 24 denotes a shaft sunk from the earth's surface to a point near the oil sand, and the galleries 1 are extended from the shaft around the tract. One or more surface wells 25 may be drilled within the tract for the purpose of introducing an explosive agent to drive the oil toward the mine wells. Ordinarily, however, excellent recoveries of oil can be obtained without the use of surface wells. In Fig. 4 the series of mine wells is denoted by numeral 26.

Instead of introducing the gas through the nipples 5, it may in some cases be desir-

able to put it in at the top of the sand. For this purpose one or more pipes 27 preferably sealed in the sand and extending nearly to the upper cap rock 4 may be provided (Fig. 5).

5 The operation of the improved method is as follows, reference being made first to Figs. 1 to 4. The nipples 5 are sealed in place at frequent intervals throughout the gallery. When operating around a square 40 acre tract 10 it is usually desirable to have 132 mine wells on each side, at distances of about 10 feet apart. A smaller number may of course be used, but the recovery of oil will not then be so complete.

15 After the nipples have been set in the cap rock, a gate valve 10 and a cross-fitting 11 or T-fitting 21 are attached to each. The cap 11' (or 21') is removed. A drill is inserted through the fitting and the open gate valve 20 into the nipple. Drilling proceeds until an opening 8 has been made for a substantial distance into the oil sand. The drill is then withdrawn to a point just below the gate valve, and this is closed.

25 The drill may now be removed without permitting fluids to escape into the gallery. After the drill is taken out, the cap 11' (or 21') on the lower arm of the fitting is replaced. Drilling in this way is safe even when 30 considerable pressure prevails in the sand.

35 In accordance with this invention, the flow of oil is expedited by forcing into the oil sand a "scrubbing" gas, that is, one which has the effect of reducing the forces of surface tension which hold the oil in the sand. In addition, the scrubbing gas preferably has the property of decreasing the specific gravity and the viscosity of the oil. For this purpose I prefer to use natural gas saturated with gasoline vapors, but other gases having similar properties may be used. Air is not so desirable, either alone or as a carrier for gasoline vapors, since it increases the viscosity of the oil. Casinghead gasoline plant vapors may 45 be used alone, when they can be obtained economically.

The first step in the use of the scrubbing gas is the formation of an "unexcavated 50 drainage tunnel" in the oil sand. As explained in Patent No. 1,634,236, above referred to, such a tunnel is an area of facilitated oil flow, generally paralleling the mine galleries. By means of heat, pressure, suction, or other expulsive agency, applied from 55 the galleries, the oil sand adjacent them is caused to yield its oil to the mine wells. Into the evacuated areas in the oil sand more oil flows, and the extent of the unexcavated drainage tunnels is thus progressively increased.

60 In the present case I prefer to use the scrubbing gas as the agency for forming the unexcavated drainage tunnel. To this end the scrubbing gas (which may be assumed to be natural gas saturated with gasoline vapors)

is introduced through the nipples 5 at intervals; for example, every fourth or fifth nipple may be used for this purpose, the others serving to collect the oil. It will be noted (Fig. 1) that the scrubbing gas passes through pipe 18, branch pipe 14 (valve 19 being open and valve 20 closed), through the open gate valve 10, and thence into the oil sand through the nipple 5 and hole 8. Alternatively, the scrubbing gas may be supplied through pipes 5' (Fig. 3).

70 The gas should be forced in under a pressure of about 10 to 100 lbs. or more per square inch, depending on the difficulty of driving the gas through the particular sand being worked. The gas spreads out from the openings 8 into the sand and forms a continuous area saturated with gas. Throughout this area the oil is charged with gas and gasoline hydrocarbons and flows rapidly by gravity into the adjacent mine wells. The scrubbing gas fills the pores in the unexcavated drainage tunnel formed as just described. As gas is continuously forced into the sand, the area 75 saturated with gas extends. The line of advancing pressure is shown diagrammatically in Figs. 1 and 2. The oil coming under the influence of the advancing gas is caused to flow, and travels toward the mine wells along the line of the heavy arrows. The oil contains dissolved gas which may be recovered at the separator mentioned above. Escape of gas as such may be substantially prevented by opening gate valves 10 only enough to permit passage of the streams of liquid oil.

80 When working along an extended line of attack from mine galleries, it is possible to maintain the scrubbing gas in most efficient condition for a considerable distance into the sand. The relatively slow pressure drop permits this. If it were attempted to inject the scrubbing gas from a surface well, the radial movement of the gas from this single point of attack would soon cause a great decrease in pressure. The capacity of the gas to hold 85 gasoline vapors would be correspondingly diminished and the effectiveness of the gas 90 would be destroyed for the most part.

95 If a satisfactory flow is established, the valves 19 in pipes 14 may be closed, and the valves 20 in pipes 15 opened. The latter pipes may then be used in the same way as the pipes 23 for the recovery of oil. Injection of gas through pipes 14 will be resumed when 100 required. For working dense or tight oil sands, it is desirable to inject the scrubbing gas near the top of the sand and allow it to 105 work its way down towards the mine wells. For this purpose a long pipe 27 is inserted 110 from the gallery into the oil sand and extending nearly up to the upper cap rock, as 115 shown in Fig. 5.

120 The success of the methods described depends in part upon the absence of fissures or 125 breaks in the oil sand and cap rocks, which 130

might vent the scrubbing gas. Any such places should be sealed, if possible. The usual sand is sufficiently gas tight to respond satisfactorily to my method.

5 It is usually more advantageous to work from beneath the sand than from above. However, the principles of the present invention are equally applicable to working from a gallery above the sand.

10 Various changes may be made in the preferred embodiments described within the scope of the appended claims, in which it is my intention to claim all novelty inherent in the invention as broadly as the prior art permits.

I claim:

1. In an installation for recovering oil from the earth by means of a mine gallery adjacent an oil sand, but spaced therefrom the improvement which comprises a series of pipes in the gallery and tapping the oil sand, a gate valve near the exposed end of certain of said pipes, an elbow connected to each said pipe below the gate valve, an oil-collecting pipe, and a connection between said elbow and said oil-collecting pipe.

2. In an installation for recovering oil from the earth by means of a mine gallery adjacent an oil sand, but spaced therefrom, the improvement which comprises a series of pipes in the gallery and tapping the oil sand, a cross-fitting on the exposed end of certain of said pipes, two conduits connected to said cross-fitting, a pipe for supplying a scrubbing gas to one of said conduits, and a separate pipe for conveying oil from the other of said conduits.

3. Apparatus according to claim 2, in which valves are provided in the conduits permitting either or both to be shut off.

4. Apparatus according to claim 2, in which a gate valve is provided between the cross-fitting and the pipe tapping the sand, said gate valve being arranged to permit the introduction and withdrawal of a drill without allowing fluids to escape into the gallery from the sand.

5. In the recovery of oil from an oil-bearing stratum, the improvement which comprises passing an agent facilitating oil flow in a stream adjacent the oil-bearing stratum but out of contact therewith, tapping off portions of the agent from the stream at frequent intervals and passing such portions into the stratum to form areas of facilitated flow therein generally paralleling the flow of the stream, and collecting oil from points near the bottom of the stratum and arranged intermediate the points at which gas is passed into the stratum.

In testimony that I claim the foregoing as my invention, I affix my signature.

LEO RANNEY.
